US0D1098004S

(12) **United States Design Patent** (10) **Patent No.:** **US D1,098,004 S**
Yu et al. (45) **Date of Patent:** **** Oct. 14, 2025**

(54) **ELECTRICAL SOCKET**

(71) Applicant: **NINGBO WELL ELECTRIC APPLIANCE CO., LTD.**, Ningbo (CN)

(72) Inventors: **Guolin Yu**, Ningbo (CN); **Zhuoming Yu**, Ningbo (CN)

(73) Assignee: **NINGBO WELL ELECTRIC APPLIANCE CO., LTD.**, Ningbo (CN)

(**) Term: **15 Years**

(21) Appl. No.: **29/903,834**

(22) Filed: **Sep. 28, 2023**

(51) LOC (15) Cl. **13-02**

(52) U.S. Cl.

USPC **D13/107**; D13/146

CLAIM

The ornamental design for an electrical socket as shown and described.

DESCRIPTION

FIG. 1 is a right, front, top perspective view of an electrical socket showing my new design;

FIG. 2 is a left, rear, bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged view of circled portion 9 in FIG. 2. The broken lines in the drawings depict portions of the electrical socket that form no part of the claimed design.

1 Claim, 9 Drawing Sheets
